UNITED STATES PATENT OFFICE

GEORGE MACKINTOSH, OF BROOKLYN, NEW YORK, ASSIGNOR TO THE TABLET AND TICKET COMPANY, OF CHICAGO, ILLINOIS, A CORPORATION OF ILLINOIS

INDICATOR BOARD FOR OFFICES AND THE LIKE

Application filed February 9, 1931. Serial No. 514,365.

The invention relates to improvements in indicator boards for offices and the like, the primary object of the invention being the provision of an improved construction of the character indicated, which is capable of economical manufacture and highly efficient in use.

Another object of the invention is the provision of a construction of the character indicated, having special provisions therein facilitating the removal and replacement of the individual indicators thereof.

Other objects will appear hereinafter.

The invention consists in the combinations and arrangements of parts hereinafter described and claimed.

The invention will be best understood by reference to the accompanying drawings forming a part of this specification, and in which

Fig. 1 is a face view of an indicator board embodying the invention, with portions broken away for the sake of clearness;

Fig. 2 an enlarged horizontal section of the same taken substantially on line 2-2 of Fig. 1;

Fig. 3 an edge view of the indicator board; and

Fig. 4 a perspective view of a locking bar employed in the construction.

The embodiment of the invention illustrated in the drawings comprises a body board 10, preferably of wood, and having channel members 11 and 12, preferably of metal, secured over the opposite edges thereof. The channel members 11 and 12 are secured in place by means of screws 13 taking through their longer legs 14, positioned against the back of the board 10, as best shown in Fig. 2.

The shorter legs 15 of the channel members 11 and 12 are positioned to project over the front face of the board 10, thereby forming retaining recesses at the opposite edges of said board, as shown. As will be noted, the channel member 12 is positioned at a slight distance from the corresponding edge of the board 10, thereby forming a channel for the reception of a locking bar 16.

The bottom of the board 10 is covered by a channel member 17 arranged to close the

lower end of the channel for the locking bar 16, and the top of the board 10 is covered by a panel member 18 which is cut short at one side so as to expose the end of the locking bar 16. The locking bar 16 is provided at 55 its upper end with an opening 19 to receive a pin, nail or the like, for withdrawal of the bar 16, the corresponding channel member 12 being provided with a notch 20 to give access to said opening 19.

The lower end or nose of the bar 16 is provided with a bevel 21 on its inner side so that when said locking bar is inserted in its channel, any individual indicators which project into said channel will be forced over into 65 proper positions relatively to the indicator board. As shown, the outer face of the board 10 is recessed for the reception of a plurality of individual indicators 22 and 23, which are of a length sufficient to traverse the 70 face of the board 10 with their ends projecting into the recesses under the legs 15. As will be noted, the arrangement is such that upon the removal of the locking bar 16, the corresponding retaining recess will be deepened to 75 such an extent as to permit the lateral shifting of the individual indicators 22 and 23 so as to facilitate the removal thereof from the board, as indicated by the dotted lines in Fig. 2. In this way it will be noted that the 80 individual indicators may be readily removed and replaced when desired.

As shown, the indicators 23 are provided with slidable concealing tabs 24 and 25 for the purpose of concealing or exposing items of information on the indicators. The specific form and arrangement of the indicators themselves constitutes no part of the present invention and therefore these parts require no further description here, beyond the statement that they are of sufficient length to traverse the face of the board and project into the retaining recesses at the opposite edges thereof.

By means of the arrangement set forth, indicator boards may be readily provided of various lengths and sizes having individual indicators thereon, which may be readily removed and replaced when desired. Obviously, the information contained on the vari- 95 100

ous indicators may be readily varied to suit a wide diversity of purposes.

While I have illustrated and described the preferred form of construction for carrying the invention into effect, this is capable of variation and modification without departing from the spirit of the invention. I, therefore, do not wish to be limited to the precise details set forth, but desire to avail myself of such variations and modifications as fall within the scope of the appended claims.

Having thus fully described my invention, what I claim as new and desire to secure by Letters Patent is:

1. A construction of the class described comprising a body having retaining recesses at opposite sides thereof; a plurality of individual indicators of a length to traverse said body with their ends fitting into said recesses; and means for locking said individual indicators in said recesses consisting of a longitudinal slide traversing the bottom of the recess at one side.

2. A construction of the class described comprising a body having retaining recesses at opposite sides thereof; a plurality of individual indicators of a length to traverse said body with their ends fitting into said recesses, the recess at one side being of sufficient depth to permit lateral shifting of said individual indicators sufficient to release the opposite ends from the opposite recess; and means for locking said individual indicators from such lateral shifting in said recess.

3. A construction of the class described comprising a body having retaining recesses at opposite sides thereof; a plurality of individual indicators of a length to traverse said body with their ends fitting into said recesses, the recess at one side being of sufficient depth to permit lateral shifting of said individual indicators sufficient to release the opposite ends from the opposite recess; and a longitudinally sliding lock bar sliding into and out of the extra depth of said recess at said one side to lock said individual indicators in said recess.

4. A construction of the class described comprising a body having retaining recesses at opposite sides thereof; a plurality of individual indicators of a length to traverse said body with their ends fitting into said recesses, the recess at one side being of sufficient depth to permit lateral shifting of said individual indicators sufficient to release the opposite ends from the opposite recess; and a longitudinally sliding lock bar sliding into and out of the extra depth of said recess at said one side to lock said individual indicators in said recess, the end of said lock bar being beveled.

5. A construction of the class described comprising a back board; retaining members at opposite edges of said back board in the form of channel members having legs pro-

jecting over the outer face of said board to form retaining recesses at opposite sides thereof; a plurality of individual indicators of a length to traverse said body with their ends fitting into said recesses; and a longitudinally sliding locking bar for locking said individual indicators from removal from said recesses.

6. A construction of the class described comprising a back board; retaining members at opposite edges of said back board in the form of channel members having legs projecting over the outer face of said board to form retaining recesses at opposite sides thereof, one of said channel members being spaced from the corresponding edge of said board to form a channel for the reception of a longitudinally slidable locking bar; a plurality of individual indicators of a length to traverse said body with their ends fitting into said recesses; and a longitudinally sliding locking bar having a beveled nose insertable in and removable from said channel.

7. As a lock for devices of the class described, the combination with a supporting frame having a retaining recess therein, of a slide traversing the bottom of the recess and arranged to reduce and limit the depth thereof.

In witness whereof, I have hereunto set my hand this 2nd day of February, 1931.

GEORGE MACKINTOSH.
